8 Claims. (Cl. 335—154)

Our present invention relates to an electromagnetic relay of the type wherein a pair of magnetizable reeds, overlappingly extending from opposite ends of a generally cylindrical envelope consisting at least in part of nonmagnetic and nonconductive material such as glass, are relatively displaceable upon selective energization of two or more inductance windings coiled around the envelope.

The use of remanently magnetizable reeds, e.g. as disclosed in U.S. Patents Nos. 3,037,085 and 3,059,075, has the advantage of allowing a short pulse to switch the relay into either a closed or an open position of its contacts, either position being subsequently maintained without additional current flow until the condition is reversed by another pulse.

In prior constructions of this type, however, relatively complex winding arrangements and/or a permanent premagnetization of one of the reeds were needed in order to bring about the desired switching action. Moreover, the amplitude range of the make and break pulses was sharply limited by the need for preventing the generation of a pulse large enough to destroy the permanent magnetization or (e.g. in the case of a differentially wound inductance coil) to prevent magnetic reversals which would tend to reclose a pair of contacts just separated by a breaking pulse.

It is, therefore, an object of our present invention to provide an improved electromagnetic relay of this character in which the aforesaid disadvantages are avoided.

A more particular object of our invention is to provide an electromagnetic relay having only two inductance coils, one for making and one for breaking, so arranged as to be operative when energized with pulses of widely varying amplitudes.

These objects are realized, in conformity with our present invention, by the provision of a first inductance winding which is coiled around at least a part of each of the two reeds, in combination with a second inductance winding coiled around a portion of only one reed while terminating short of the overlapping extremities of the two reeds. The two coils are advantageously wound, in a manner known per se, on the outside of the envelope to which they may be fastened, pursuant to another feature of our invention, by having terminal turns thereof soldered onto the envelope itself.

The two reeds, or at least one of them, are suitably biased to maintain their overlapping extremities spaced apart in the absence of magnetic attraction. Such magnetic attraction will come into play when the first winding is energized, owing to the fact that the two portions of this winding magnetize the respective reeds in aiding relationship so that their confronting ends are of opposite polarity. When these ends attract each other, the remanent magnetism of the reeds maintains the connection even after the contact-closing pulse has disappeared. Subsequently, upon the passage of a pulse of opposite polarity through the other winding, the magnetization of the reed embraced by that winding is reversed so that the confronting extremities now repel each other; thus, the circuit is now opened.

The magnitude of the closing pulse need only be suf-

2

ficient to effect substantial saturation of the two reeds, it may, however, be many times larger without adverse effect. The opening pulse, conversely, need only be strong enough to overcome the mutual attraction of the reeds due to their remanent magnetization; this pulse, too, may rise to several times that minimum amplitude without affecting the remanent magnetization of the other reed, i.e. of the one not enveloped by it, to an extent which might lead to a reclosing of the circuit. While the reeds could be biased into their normally open-circuited position by inherent resiliency, we prefer to connect their mutually remote extremities with respective terminal members by short interposed leaf springs of electrically conductive material so that the magnetizable material of the reeds (e.g. ferrite) may be chosen independently of the required biasing force.

Although the two windings could mutually overlap, at the expense of a slight increase in the stray flux field of the break winding if it were to surround part of the make winding, we prefer to dispose the two windings in axially spaced relationship directly on the wall of the envelope. This envelope, in turn, advantageously is filled with an inert (i.e. nonoxidizing) gas.

In a particularly advantageous embodiment, the overlapping tips of the reeds are coated with a highly conductive but nonmagnetic contact metal interdiffused with the magnetizable material of the reeds. This contact metal is preferably silver, gold, or one of the elements of platinum group such as rhodium. Its presence, as is known, per se, is designed to prevent arcing and chattering while insuring a clean break in response to relatively small circuit-opening pulses.

The invention will be described in greater detail with reference to the accompanying drawing whose sole figure illustrates an electromagnetic relay according to the invention, shown in axial section, along with associated circuitry indicated diagrammatically.

The relay shown in the drawing comprises a tubular glass envelope 1 having sealed-in conductors 4 and 4' axially extending into it from opposite ends. A pair of remanently magnetizable ferrite reeds 2 and 2' are secured to respective terminals, constituted by the inner ends of conductors 4 and 4', by way of short leaf springs 3 and 3'. Reeds 2 and 2' have overlapping extremities 5 and 5' biased into a normal spaced-apart position by the resiliency of springs 3 and 3'. These overlapping extremities are coated with a highly conductive contact metal, as described above, which is interdiffused with the ferrite material of the respective reeds.

The interior of the hermetically sealed envelope 1 is filled with a nonoxidizing atmosphere, such as a gas mixture consisting of 90% nitrogen and 10% hydrogen by weight.

Two windings 7 and 7' are coiled around the outer surface of tube 1, the first winding 7 extending over the full length of reed 2 and a fraction of the length of reed 2' whereas the second winding 7' embraces only a part of the length of reed 2' not enveloped by the winding 7. It will be noted that winding 7' terminates short of the overlapping ends 5 and 5' of the reeds. Winding 7 has terminals 6a and 6b connected across a source of contact-closing pulses here shown diagrammatically as a battery 8 and a switch 9. Winding 7' has its terminals 6a, and 6b connected across a similar source of contact opening pulses represented by a battery 8' and a switch 9'. As indicated by the designations N, S and N', S', the polarity of the magnetic flux traversing reeds 2 and 2' upon energization of winding 7 is opposite the polarity of the magnetic flux induced in reed 2' upon energization of winding 7'.

Windings 7 and 7' have terminal turns 7a, 7b and

7a', 7b' soldered onto the outer surface of glass tube 1 so as to be held in position on that tube.

The springs 3 and 3' advantageously consist of hardened and tempered carbon steel with a carbon content of about 0.8% to 1.1% by weight. The magnetic-flux path represented by the reeds and the springs may be saturable upon application of a coercive force equivalent to about 1200-3200 ampere-turns per meter and, when thus saturated, may be permeated by a flux of approximately 1 to 1.7 gauss.

The treatment of the ferrite reeds with the contact metal 5 or 5', e.g. silver, gold or rhodium, may be carried out by electrodepositing this metal upon the extremities of the heat-treated reeds and thereafter subjecting these reeds to a temperature of, say, 600-800° C. for a period of about 10 minutes to two hours.

Closure of switch 9 for a short period, e.g. 10 μ sec., will generally suffice to saturate the reeds 2 and 2' so that their extremities 5 and 5' attract each other to close the main circuit through terminal leads 4 and 4'. This condition is maintained by the remanent magnetism of the reeds until momentary closure of switch 9', for a similar interval, reverses the magnetization of reed 2' to open the contacts. In a typical system of this nature, the contacts close approximately 1 to 3 μ sec. after application of the making pulse to winding 7 and open about 50 μ sec. after passage of the breaking pulse through winding 7'. Naturally, the switches 9 and 9' are representative of transistors and other electronic switching devices conventionally used in such systems.

The relative insensitivity of our improved relay to variation in pulse amplitudes makes it particularly useful in any circuit in which several such relays are to be connected in cascade, i.e. wherein the make or break winding of one relay lies in series with either a make winding or a break winding of another relay. Thus, the relay shown and described may be used in cross-bar switches of telephone exchanges and similar installations. It is also easily compatible with printed circuitry, thanks to its compact construction.

We claim:

1. An electromagnetic relay comprising a sealed envelope of generally cylindrical shape; a first and a second reed of remanently magnetizable material extending substantially axially within said envelope from op-

posite ends thereof, said reeds having overlapping extremities within said envelope and being provided at their opposite extremities with terminals for connecting them in an external circuit, at least one of said reeds being resiliently biased for keeping said overlapping extremities separated in the absence of magnetic attraction; a first inductance winding coiled around at least part of the length of each of said reeds; and a second inductance winding coiled around a portion of only one of said reeds but terminating short of said overlapping extremities.

2. A relay as defined in claim 1 wherein said windings are axially spaced from each other.

3. A relay as defined in claim 1 wherein said overlapping extremities are provided with confronting surfaces having coatings of highly conductive but nonmagnetic contact metal interdiffused with said magnetizable material.

4. A relay as defined in claim 3 wherein said contact metal is selected from the group which consists of silver, gold and rhodium.

5. A relay as defined in claim 1 wherein said windings are coiled around said envelope and have terminal turns soldered onto same.

6. A relay as defined in claim 1, further comprising switch means for alternately connecting said windings across a source of current with mutually opposite directions of polarization.

7. A relay as defined in claim 1 wherein each of said 30 reeds is provided with a leaf spring connecting the opposite extremity thereof to the respective terminal for biasing said overlapping extremities into a separated position.

8. A relay as defined in claim 1 wherein said envelope 35 is filled with a nonoxidizing gas.
